United States Patent Office.

JOHN W. BENTLEY, OF WOONSOCKET, RHODE ISLAND.

Letters Patent No. 76,042, dated March 31, 1868.

IMPROVEMENT IN MACHINE FOR MANUFACTURING CLOUDED YARN.

The Schedule referred to in these Letters Patent and making part of the same.

TO ALL WHOM IT MAY CONCERN:

Be it known that I, JOHN W. BENTLEY, of Woonsocket, in the county of Providence, and State of Rhode Island, have invented a new and useful Improvement in the Manufacture of Spotted or Clouded Yarn; and I do hereby declare that the following is a full, clear, and exact description thereof, which will enable others skilled in the art to make and use the same, reference being had to the accompanying drawings, forming part of this specification, in which—

Figure 1 is a front view of my improved machinery for making clouded yarn.

Figure 2, a vertical section of the same, taken in the line $x'x$, fig. 1.

Similar letters of reference indicate like parts.

This invention relates to an improvement in the manufacture of clouded or spotted yarn, and consists in rollers and change-gear, operating intermittently, attached to an ordinary spinning-frame, by which a portion of the threads of one color are continuously spun, while roping of another color is combined with them in such manner as to produce changes in the color or shade of the yarn at regular distances apart, as hereinafter more particularly described.

The drawing represents an ordinary spinning-frame and rollers, to which my improvements are attached. Two or more threads of any color, coming from the spool E, pass down between the ordinary rolls F N, and down in front of the additional rolls H I, and under the small roll L, coming in contact with the roping of some other color running from a sliding spool, shown in red, fig. 2, resting on the friction-roll or drum C. After the roping passes between the rolls H I, the two colors of the roping and the thread from the spool E run together, and are spun in the usual manner, but this combination continues only so long as the motion of the roll C and the rolls H I is continued, which motion is intermittent in its nature, being operated by a change-gear wheel, G, engaging the carrier-gear K during a part of its revolution only. The carrier-gear K works into the gear J, which drives the roll I, and also works into a train of gear-wheels, a b c, as shown in the drawing, to drive the drum C. Thus the drum C and the rolls H I have a corresponding intermittent motion, while the rolls F N have a continuous or constant motion; and while the thread from the spool E is continuously spun, the roping from the spool resting on the drum C combines with thread to run the different colors together, in spinning only, while the change-gear G engages the carrier-gear K, and the roping breaks whenever the change-gear disengages, and the motion of the drum and the rolls H I is suspended, thus cutting off the combination of different colors for a part of the revolution of the change-gear; but as soon as the change-gear engages the carrier-gear K, the roping again starts, and is spun with the thread, as before, whereby a spotted or clouded yarn is produced by the union of the two colors at regular distances.

The spotting or clouding of the yarn may be varied by making the change-gear so as to operate differently, by engaging and disengaging the carrier-gear at different parts of its revolution.

The small-roll L receives its motion continuously, by a band, d, from the roll N.

Having thus described my invention, what I claim as new, and desire to secure by Letters Patent, is—

The combination of the additional rolls H I L, and the change-gear G, with a common spinning-frame, arranged and operating substantially as and for the purposes herein shown and described.

JOHN W. BENTLEY.
